UNITED STATES PATENT OFFICE.

LOUIS STROHACKER, OF FREEPORT, ILLINOIS, ASSIGNOR TO STRUCTO MANUFACTURING COMPANY, OF FREEPORT, ILLINOIS, A CORPORATION OF ILLINOIS.

TOY STEAM SHOVEL.

Original application filed September 12, 1924, Serial No. 737,270. Divided and this application filed February 12, 1925. Serial No. 3,653.

To all whom it may concern:

Be it known that I, LOUIS STROHACKER, a citizen of the United States, and a resident of Freeport, Stephenson County, and State of Illinois, have invented certain new and useful Improvements in Toy Steam Shovels, of which the following is declared to be a full, clear, and exact description.

This invention relates to toy steam shovels and its principal object is to provide an amusing, entertaining and instructive toy for children, which shall simulate the action of a steam shovel or dredge in picking up a load, elevating it and dumping it. In my 10 pending application for patent on toy steam shovel, filed September 12, 1924, Serial No. 737,270, is illustrated one form of mechanism for operating the shovel proper and the trap door thereof, and in the present 15 application, which has been divided out of said pending application, another form of shovel operating and trap door controlling mechanism is disclosed. The present form has several novel characteristics, namely: It 20 is considerably cheaper to construct, has less moving parts and can be sold at a lower price. One of the objects of the present invention is to provide a novel arrangement of parts, operated by a single cord or other 25 flexible connection, for swinging up the shovel and dumping the load when the scoop reaches a certain raised position. With these and other object and advantages in 30 view this invention consists in the several novel features hereinafter fully set forth and claimed.

The invention is clearly illustrated in the drawing accompanying this invention in which:—

40 Fig. 1 is a side elevation of a toy steam shovel embodying a simple form of the present invention; Fig. 2 is a front elevation of the shovel proper; Fig. 3 is a side elevation of a certain latch which operates to hold the trap door in closed position; Fig. 4 is a cross section through the shovel arm taken on the line 4—4 of Fig. 2 and Fig. 5 is a side elevation showing the invention applied to a toy dredge.

50 Referring to said drawings and first to Figs. 1 to 4 inclusive, which illustrate the preferred embodiment of the present invention, the reference character 6 designates the supporting member of a running gear, 55 which is mounted on wheels 7 and upon metal pieces 8 secured upon its outer sides,

which is supported a steam boiler like structure 9. These parts may be made of light metal work formed up by suitable dies and secured together in any suitable manner.

Secured to the forward part of the supporting member 6 are two posts, one of which is seen at 10 in Fig. 1, and secured near the rear part of the support 6 are two braces, one of which is seen at 12. The upper ends of these posts and braces are connected by a headed pin, or other device 19, which forms the fulcrum for the shovel. The braces 12 project slightly beyond their connection with the posts 10 and their extreme ends are spaced apart and secured together by a rivet 19. The posts and braces incline from the sides of the support 6 toward each other at their upper ends as will be more clearly seen in Fig. 2 where the posts and braces are shown in dotted lines. Said supporting member 6, posts 10, and braces 12 form the support upon which the shovel is fulcrumed, as will be presently explained.

Fulcrumed on the pivot pin 19 is the 80 shovel 13, and said shovel is movable from a down or loading position, seen in dotted lines in Fig. 1, to a second or dumping position, where the scoop portion 14 occupies a position slightly above that shown in solid 85 lines in Fig. 1. In its preferred form the shovel comprises a scoop or receptacle 14 open at the front 14^a and back 14^b thereof, and having a trap door or hinged bottom 15, hinged at the back of the scoop, to ears 14^c 90 located on the top wall 17 of the scoop. Preferably the sides of the trap door are bent up to form flanges that overlie the rear portions of the side walls of the scoop. Secured to and projecting up from the top 95 wall 17 of the scoop, is the shovel arm 18, which is preferably formed of two spaced strips or bars of metal, said shovel arm extends between the two posts and braces 10, 12, and the pivot pin 19 passes through the 100 shovel arm and forms the fulcrum upon which the shovel is swing up and down.

Slidably mounted on the shovel arm 18, between the two members thereof, is a latch 30 (see Fig. 3) which is formed with a finger 31, adapted, when in one position of the latch, to underlie the trap door 15 and hold it in its closed position. In its preferred form said latch 30 has two channel like metal pieces 32 secured upon its outer sides,

and the flanges 33 of said channel like pieces lie along the outer edges of the two members of the shovel arm 18. The exact form of latch is not material to this invention, broadly speaking, but it forms a very satisfactory latch for the purpose intended. The main portion of the latch and the channel like members thereof are riveted together and these parts are located between the two members of the shovel arm. The latch is guided to move lengthwise on the shovel arm by the flanges 33 which engage with the edges of the two members of the shovel arm. The latch is slidable along the shovel arm and when permitted to do so, it falls by gravity to the position shown by the dotted lines in Fig. 1 that illustrates the down or loading position of the shovel. The latch may, however, be drawn along the shovel arm so as to move the supporting finger 31 from beneath the trap door to thereby permit the trap door to open and swing down, and this position of the latch is shown by the dotted lines in the up or dumping position of the shovel. The shovel and latch are operated by mechanism which will now be described.

Secured to the latch, as for instance, by hooking one end into a hole therein, is a latch actuating link 34 which may comprise a piece of rod or wire. It extends between the two members of the shovel arm from the latch to the free end thereof when it strikes against rivets 35 that connect the ends of the two members of the shovel arm. The free end of the link 34 is formed into an eye 36, and secured in said eye of the link 34 is a cord or other flexible connection 20, which runs to a winding drum 22, to which it is secured. In the form illustrated in Fig. 1 the winding drum 22 is contained in the hollow of the boiler 9 and is mounted on a shaft 24 which is journaled in the side walls of the boiler and has a hand crank 23 formed upon one outer end. The cord or other flexible connection 20, passes through an opening in the front of the boiler 9.

The winding drum 22 may be rotated in either direction by turning the crank 23, thereby winding up the cord or other flexible connection 20, thereon, and drawing down upon the free end of the shovel arm 18, and swinging up the other end and therewith the scoop. During the movement of the scoop from the loading position, (shown by the dotted lines in Fig. 1) to the dumping position (shown in full lines) the finger 31, of the sliding latch is in engagement with the trap door 15, thereby holding it closed, and the eye 36 of the latch operating rod or eye is held close to the rivets or pins 35. When the shovel reaches the position at or close to the one shown in full lines in Fig. 1 the pull upon the latch actuating link 34, is in a direction tending to move it lengthwise

of the shovel arm, and when such position is reached the further rotation of the drum causes the cord or other flexible connection 20 to pull the latch actuating link outward into the position indicated by the dotted lines in the up position of the shovel, thereby drawing back the latch and disengaging its finger from the trap door, permitting the trap door to open and swing by gravity into the position shown by the dotted lines in the up position of the shovel. When the crank is released or turned in the opposite direction to which it was turned to raise the scoop, the cord or other flexible connection 20, is paid out from the drum, thereby permitting the scoop to swing down and when it approaches its down position, the trap door swings toward its closed position and the latch drops to its effective or locking position, drawing the latch actuating link 34 down with it. When the shovel reaches its down position, as shown by the dotted lines in Fig. 1, the trap door is fully closed and the latch in effective position locking it shut.

It will be seen that the cord or other flexible connection 20, being secured to the latch actuating link 34, it operates to swing the scoop upwards, when the cord is pulled backwards and that when the shovel arm reaches a predetermined position, the cord or flexible connection operates to move the latch actuating rod lengthwise of the shovel arm, thereby disconnecting the latch from the trap door and permitting it to swing by gravity to an open position.

In the form of the invention illustrated in Fig. 5 it is shown as applied to a toy dredge of which 6^a is the body portion which simulates a scow. The post or mast 10^a is secured to the front end of the body 6^a and is braced by the brace bar 12^a. The shovel 13^a may be of the same form and construction as the one of the form shown in Figs. 1 to 4. It is fulcrumed on the pin 19^a which connects the post or mast and brace. The drum 22^a is shown as mounted on the brace bars 12^a, it is manipulated by a crank 23^a. The cord, cable or chain 20^a is secured to the drum 22^a, and is trained around a roller 29^b mounted on the body 6^a, and around the pin 35^a at the end of the shovel arm 18^a. The rod or wire link 34^a is fastened to the latch 30^a, and extends to the end of the shovel arm 18^a where its end is formed into an eye and the cord, cable or chain 20^a is secured to it. The brace bars 12^a project beyond the post or mast 10^a and are connected by a pin 19^b which acts as a stop for the shovel arm.

In this form of the invention, when the drum is rotated, and the cable or chain wound up thereon, the pull of the cable or chain is exerted to swing the shovel in the direction of the arrow *a*, until the acute

angle between the cable and shovel arm is increased to an obtuse angle or, in other words, until the cable and shovel arm form almost a straight line, whereupon the pull 5 on the rod or wire link 34^a is in a direction almost lengthwise of said link, and the latter is thereupon drawn back and therewith the latch, thus releasing the trap door and permitting it to open. When the drum is 10 turned in the reverse direction, the cable is paid out, thereby permitting the shovel to swing downward and when it approaches the position shown the latch 30^a and link 34^a drop into the locking position shown and 15 lock the trap door shut.

More or less variation of the exact details of construction is possible without departing from the spirit of this invention; I desire, therefore, not to limit myself to the 20 exact form of the construction shown and described, but intend, in the following claims, to point out all of the invention disclosed herein.

I claim as new, and desire to secure by 25 Letters Patent:

1. In a toy, a body portion having a support extending up therefrom, a shovel having an arm fulcrumed on said support and a scoop at one end, said scoop having a 30 discharge opening controlled by a trap door, latch mechanism mounted on said arm and having a latch arranged to lockingly engage said trap door, a drum, and a flexible connection between said drum and latch 35 mechanism for actuating said shovel and latch mechanism.

2. In a toy, a support, a shovel having a shovel arm fulcrumed on said support, a scoop on one end of said shovel arm, and a 40 trap door closing the discharge opening of said scoop, a latch on said shovel arranged to lock said trap door in its closed position, and a flexible shovel and latch operating connection, connected to said latch and extending from the free end of said shovel arm.

3. In a toy, a support, a shovel having a shovel arm fulcrumed on said support, a scoop on one end of said shovel arm, and a 50 trap door closing the discharge opening of said scoop, a slidable latch on said shovel

having a finger arranged to lock said trap door in its closed position, and a flexible shovel and latch operating connection, connected to said latch and extending from the 55 free end of said shovel arm.

4. In a toy, a support, a shovel having a shovel arm fulcrumed on said support, a scoop on one end of said shovel arm, and a trap door closing the discharge opening of 60 said scoop, a slidable latch slidably mounted on said shovel arm and having a finger adapted to underlie and lock said trap door in its closed position, and a flexible shovel and latch operating connection, connected to 65 said latch and extending from the free end of said shovel arm.

5. In a toy, a support, a shovel having a shovel arm fulcrumed on said support, a scoop on one end of said shovel arm, and a 70 trap door closing the discharge opening of said scoop, a latch on said shovel arranged to lock said trap door in its closed position, a link secured to said latch and movable lengthwise of the shovel arm, and a flexible 75 shovel and latch operating connection secured to and extending from said link.

6. In a toy, a support, a shovel having a shovel arm fulcrumed on said support, a scoop on one end of said shovel arm and a 80 trap door closing the discharge opening of said scoop, a slidable latch on said shovel having a finger arranged to lock said trap door in its closed position, a link secured to said latch and movable lengthwise of the 85 shovel arm, and a flexible shovel and latch operating connection secured to and extending from said link.

7. In a toy, a support, a shovel having a shovel arm fulcrumed on said support, a scoop on one end of said shovel arm, and a trap door closing the discharge opening of 90 said scoop, a slidable latch slidably mounted on said shovel arm and having a finger adapted to underlie and lock said trap door in its closed position, a link secured to said latch and movable lengthwise of the shovel 95 arm and a flexible shovel and latch operating connection secured to and extending from said link.

LOUIS STROHACKER.
